UNITED STATES PATENT OFFICE.

DAVID DAVIS, OF NEWBURG, OHIO, ASSIGNOR OF ONE-HALF TO JOHN M. DAVIDSON, OF SAME PLACE.

SMOKE-PREVENTING FURNACE.

SPECIFICATION forming part of Letters Patent No. 317,522, dated May 12, 1885.

Application filed January 24, 1885. (No model.)

To all whom it may concern:

Be it known that I, DAVID DAVIS, a citizen of the United States, residing at Newburg, in the county of Cuyahoga and State of Ohio, 5 have invented a new and useful Improvement in Smoke-Preventing Furnaces for Heaters, Steam-Boilers, &c., of which the following is a specification, reference being had to the accompanying drawings.

10 My invention relates to a furnace for heaters, steam-boilers, &c.; and it has for its object to provide a furnace which shall be simple in its construction, cheap to manufacture, and effective in its operation.

15 In furnaces as heretofore constructed the draft has been upward. Coal of all kinds contains a percentage of incombustible material which, in the ordinary furnace, is melted and runs to the grate-bars, at which point it enters 20 counters the upward cold-air draft and is solidified, forming an impervious mass known as "clinkers," which check the draft and make it necessary to clean the grate at frequent intervals, involving labor, loss of time and fuel, 25 for with the utmost care a percentage of the combustible material is raked out with the clinkers.

My invention consists in the improved construction whereby the above objections are 30 overcome, and in the combinations of parts hereinafter fully described, and pointed out in the claims.

In the drawings, Figure 1 is a front elevation of a furnace constructed in accordance 35 with my invention. Fig. 2 is a plan view of the same. Fig. 3 is a longitudinal vertical section, and Fig. 4 is a transverse section.

In the accompanying drawings, in which like letters of reference indicate corresponding 40 parts in all the figures, A represents the fire pot or bed, which is formed with downwardly-converging side walls, a b, the side walls b being formed with ledges c for the reception of the grate-bars d. The top of the fire pot or 45 bed is open, as shown, and below the fire-pot is provided a chamber, C, the bottom of which inclines toward the forward or front end of the furnace.

B represents a wall which extends upwardly in an inclined direction from the bottom of the furnace, said partition-wall being angular at its upper end, as shown at D, and said angular portion D being connected with

the front wall of the furnace. A hole or opening, e, is formed in the partition-wall B at 55 the lower end thereof, and said hole or opening is adapted to be closed by any suitable construction of plug.

It will be seen that by forming the partition-walls B D a chamber, E, is formed, which is 60 closed by a door, E'. A passage, G, is formed just below the grate-bars and above the chamber E, which passage is closed by a door, H, by opening which entrance may be had to the interior of the furnace for the purpose of re- 65 pairing the same.

I represents the flue leading to the boiler, which flue communicates with the chamber C, said flue being convexo-plano in cross-section and inclining upwardly, as shown. 70

In starting the fire the fuel is spread evenly over the grate-bars and kindled from the top. It is then left to burn until the bars are covered with glowing embers, when fresh fuel is added to the top. It will thus be seen that as 75 the draft is downward upon the fire the incombustible materials will be melted and run through the grate-bars, and will not solidify, inasmuch as they encounter no cold air, the said incombustible material remaining in a liquid 80 condition until drawn off. It will be obvious that by this arrangement the grate-bars are kept entirely free, so that a free draft is insured, and, further, it obviates the necessity of continually raking the fire to remove clinkers 85 therefrom, thus saving time and fuel.

Having fully described my invention, what I claim as new, and desire to secure by Letters Patent, is—

1. The combination, with the fire-pot, of 90 the chamber C, the flue I, and the partition B, having an opening and forming a chamber, E, substantially as set forth.

2. The combination, with the fire-pot, of 95 the chamber C, flue I, passage G, closed by a door, and the chamber E, having an opening, e, in the inclined wall thereof, substantially as set forth.

In testimony that I claim the foregoing as my own I have hereto affixed my signature in 100 presence of two witnesses.

DAVID DAVIS.
